BALL RETARDER

Lloyd Stanley Breen, New Toronto, Ontario, Canada, assignor to The Brunswick-Balke-Colender Company, a corporation of Delaware

Application December 10, 1949, Serial No. 132,279

14 Claims. (Cl. 273—47)

1

This invention relates to a ball retarder for bowling alleys.

Ball retarders are employed in conjunction with a ball return track of a bowling alley to retard the velocity of a ball and eject it slowly into a storage rack. These retarders are used to prevent injury to bowlers when a ball enters a storage rack too rapidly and strikes a ball therein causing it to be propelled forwardly and sometimes bump against the hand of a bowler selecting a ball from the rack. The ordinary ball retarders are usable only with a ball of a certain size. The present invention is concerned with a ball retarder that will retard individual balls of different sizes, such as duck pin balls, five pin balls and ten pin balls and any combination of such balls rolling along the track in proximity.

An object of this invention is to provide an improved ball retarder for retarding balls of different sizes.

Another object of this invention is to provide a ball retarder for retarding a ball of one size while blocking a following ball of another size.

More specifically the invention involves the provision of a rotatable device having a plurality of ball engaging members spaced different distances from a ball return track and wherein a first set of said members are normally in a position to engage relatively smaller balls and a second set of said members are normally in a position to allow a smaller ball to pass thereunder or to engage a relatively larger ball but movable to a position to engage a smaller ball and a third set of engaging members normally in a position not to engage either relative size of ball but movable to a position to engage a relatively large ball.

Other objects and advantages of the invention will become apparent from the following description of two embodiments of the invention taken in connection with the accompanying drawings, in which:

Fig. 1 is a fragmentary side elevational view of a portion of a ball return track including storage racks and showing a ball retarder of this invention in ball retarding position.

Fig. 2 is a fragmentary side elevational view showing the ball retarder of Fig. 1.

Fig. 3 is a plan view of the ball retarder of Fig. 2.

2

Fig. 4 is a vertical sectional view taken substantially through the center of the ball retarder of Figs. 2 and 3.

Fig. 5 is a fragmentary perspective view showing the ball retarder in conjunction with a pair of differently sized balls.

Fig. 6 is a fragmentary side elevational view of a second embodiment of the invention showing in solid lines the retarder in ball releasing position, and in dotted lines the retarder in normal ball obstructing position.

Fig. 7 is a vertical sectional view taken substantially along line 7—7 of Fig. 6.

Fig. 8 is a fragmentary perspective view showing the ball retarder of Figs. 6 and 7 in conjunction with a pair of differently sized balls.

While the invention has been illustrated in the accompanying drawings as applied to two different embodiments, it should be understood that the invention is susceptible of modifications and changes without departing from the spirit and scope of the invention as set out in the appended claims.

In Figs. 1 to 5, inclusive, there is illustrated one embodiment of the new ball retarder 10. In Fig. 1 this ball retarder is shown applied to a usual ball return track 11 that is provided with the ordinary downwardly inclined main track portion 11a, a portion 11b inclined sharply upwardly to lessen the momentum of the ball, and upper and lower storage racks 12 and 13 on which balls may be stored until they are used. The upper storage rack 12 is connected to the top of the upwardly inclined portion 11b by a generally downwardly inclined portion 11c to insure the balls rolling onto the upper storage rack 12. As soon as the upper storage rack 12 is substantially filled with balls, they are moved, usually by hand, to the lower storage rack 13, as illustrated in Fig. 1.

In order to retard the movement of the balls and eject them slowly on to the storage rack 12, the ball retarder 10 is preferably positioned adjacent the downwardly inclined portion 11c of the ball return track, as shown in Fig. 1.

The ball retarder comprises a cradle 14 mounted for rotation about an axis. As shown in the drawings, the cradle is rotated on an axle 15 extending through the portion 11c of the ball return track. As is shown in Fig. 2, the axle 15 is

located nearer the front of the cradle than the rear so that the center of gravity of the cradle is to the rear of the axis of rotation.

The cradle 14 includes a pair of side members 16 located on opposite sides of the ball return track 11c and connected together by means of the axle 15, rod 17 and rod 18 to form the cradle. The rod 17 also acts as a positioning member in a manner more fully set forth hereinafter. As can be seen in Fig. 4, the axle 15 extends through an annular bearing collar 19.

The cradle 14 has a rear portion 14a extending above the track and a front portion 14b extending substantially beneath the track when the cradle is in normal ball obstructing position, as shown in Figs. 1 and 2. The rear portion 14a of the cradle is provided with a pair of first rollers 20 normally located a short distance above the track and a pair of second rollers 21 located normally a greater distance above the track and between the first rollers 20 and axle 15. The front portion 14b of the cradle is provided with a pair of third rollers 22 normally located out of ball engaging position and also spaced on opposite sides of the track. As shown in Fig. 3, each of the rollers 20, 21 and 22 is mounted on a side member 16. These rollers are preferably of a resilient material, such as rubber, and each roller is mounted for rotation on a short pin 23 extending from a side member 16. The bottom of the front portion 14b of the cradle is provided with a resilient bumper 24. This resilient bumper cooperates with the stop abutment 11g on the track to limit clockwise rotation of the cradle.

The first rollers 20 are normally spaced above the ball return track 11 a distance such that they will be contacted by a small ball, such as a duck pin ball 25 (Figs. 5 and 8) or a five pin ball 26 (Fig. 5). The second rollers 21 are normally spaced above the ball return track a distance such that the small balls will normally pass thereunder. However, when the cradle has been rotated to ball releasing position by contact of the small ball with the first rollers 20, the second rollers 21 will be lowered a distance sufficient to intercept a following small ball. The second rollers 21 are so located that they are always in position to intercept a largest ball, such as a ten pin ball 27 (Figs. 1, 6, 7 and 8).

The third rollers 22 are normally partially beneath the ball return track 11, as shown in Fig. 2. These rollers 22 are spaced apart a distance such that the small balls, such as the duck pin or five pin balls, will pass therethrough irrespective of the position of these rollers above the track. However, these third rollers are so spaced that they will intercept a following largest ball, such as a ten pin ball, when a first largest ball is in the retarder and rotating the cradle to ball releasing position by contact of this largest ball with the second rollers 21. As is shown in Fig. 3, each pair of rollers 20 and 21 are closer together than are the third rollers 22.

When the cradle is in its normal position, as shown in Fig. 2, the third rollers 22 are located in side cavities 11d in the ball return track 11. Immediately beneath the first rollers 20 are provided openings 11e in the ball return track through which the rollers 20 pass when the cradle is rotated to ball releasing position by means of the contact of a largest ball with the second rollers 21. When in this position, the second rollers will be moved to a point adjacent side plates 28 on the bottom of the track 11c and into cut out portions 11f.

In order to hold the cradle in its normal ball obstructing position and to release a ball gently from the cradle, there is provided a yieldable means urging the cradle into this normal position. In the embodiment shown in the drawings, this yieldable means comprises a hollow cylinder 29 having its bottom end rotatably mounted on a rod 30 extending between the sides of a hollow downwardly projecting member 31.

5 Located within the hollow cylinder 29 is a piston 32 attached to a hollow tube 33 extending through the top of the cylinder. This piston extends through an opening 29a in a cap 34 which serves as a closure for the upper end of the cylinder. The top of the hollow tube 33 is rotatably attached by means of a collar 35 and a rod member 36 to the side members 16 of the cradle 14. This arrangement is shown in section in Fig. 4 and in side elevation in Fig. 7.

10 The bottom of the piston 32 is provided with a relatively large opening 32a narrowing at the top in the shape of a frustum of a cone and communicating with the interior of the hollow tube 33. The lower end of this tube is supported in a boss 32b on the upper surface of the piston 32. This boss and the adjacent section of the hollow tube 33 are provided with small openings 32c communicating with the interior of the hollow tube 33. The interior of the piston 29 is filled to a 15 level above the highest level of the piston 32 with an oil. When the piston is moved downwardly by rotation of the cradle 14 in a clockwise direction, as viewed in Fig. 4, oil flows from beneath the piston through the bottom opening 32a into the interior of the bottom end of the tube 33 and out the small openings 32c. When the piston is moved upwardly, the oil flows in a reverse direction through these openings in the bottom of the tube.

20 In order to yieldingly restrain rotation of the cradle in the above clockwise direction, the chamber formed by the openings 32a is provided with a ball 37 having a diameter greater than the smallest diameter of the opening 32a, but less than the largest diameter thereof. This ball is held within the opening 32a by means of a spider 38. If the ball 37 were free to move upwardly in the opening 32a, it would completely close this opening and prevent oil flowing through the opening 32a and connected passageway when the piston 32 moved downwardly. However, the ball is normally held a short distance away from the top of the opening 32a so as to permit restricted flow of oil around the ball into the bottom of the tube 33 and out the opening 32c. The means for so holding the ball consists of a rod 39 extending down in the interior of the tube 33 and having a reduced end 39a bearing against the ball. This rod has a threaded upper end 39b engaging similar threads on the interior of the tube 33 at the top thereof. With this arrangement, the position of the ball 37 may be adjusted as desired to permit the required flow of oil upwardly through the passageway 32a around the reduced end 39a on the rod and out the openings 32c. When the piston is moved upwardly, the flow of oil will force the ball 37 down against the spider 38 so that the flow will be more rapid.

25 Located within the cylinder 29 is a helical spring 40 extending between the bottom of the cylinder and the bottom of the piston 32. This spring provides additional resistance to the movement of the piston in a downward direction.

30 With the cylinder, piston and spring arrangement discussed above, the cradle of the ball re-

retarder will be rotated slowly to ball releasing position because of the resistance of the spring 40 and the restricted flow of the oil. However, after a ball has passed through the retarder, the cradle will be returned more rapidly to its normal ball obstructing position by the action of the spring 40 and the relatively free flow of oil downwardly through the piston 32. The return movement of the cradle under the influence of the spring 40 is limited by the positioning rod 17 which engages the side plates 28 on the bottom of the track 11c.

The operation of the retarder on largest ten pin balls is illustrated in Fig. 1. When the ball rolls down the ball return track 11a from the pin end of the alley, it is rolling at a fairly rapid speed, and has considerable momentum. When the ball rolls up the steeply inclined portion 11b of the track, however, it loses a major portion of this speed and momentum, and rolls into the retarder along the inclined part of the track portion 11c at a considerably reduced speed. When the largest ball rolls into the retarder, it strikes the upwardly extending second rollers 21. The momentum of the ball causes the retarder to rotate around its axle 15 in a clockwise direction, as viewed in Fig. 1. Due to the construction of the piston 32 in the cylinder 29 and the force of the spring 40, this clockwise rotation is relatively slow so that the ball is ejected on to the storage rack 12 at a slow speed. When the retarder is thusly rotated by a ball therein, the front portion 11b of the retarder is raised above the return track to intercept a largest ball that is following too closely behind the first ball. After the first ball has been ejected from the retarder, the spring 40 causes the retarder to be rotated in a counter-clockwise direction until it reaches its normal ball obstructing position, shown in Figs. 1, 2 and 4.

The operation of the retarder on balls of different sizes is illustrated in Fig. 5. In this figure the first ball is a duck pin ball 25 and the second ball is a five pin ball 26. The small duck pin ball 25 is intercepted by the first rollers 20 as the second rollers 21 are spaced a sufficient distance apart and above the return track to permit either a duck pin ball 25 or a five pin ball 26 to pass thereunder. However, when the small ball 25 contacts the first rollers 20 to rotate the retarder, the second rollers 21 are lowered a distance such that they will intercept a following small ball whether it is a duck pin or a five pin ball. In Fig. 5, the first ball 25 has rotated the retarder to ball releasing position and the immediately following ball 26 has been intercepted by the second rollers 21. As soon as the first ball 25 is ejected from the retarder, the spring 40 returns the retarder to its normal position and the second ball then passes under and between the second rollers 21 so that it in turn contacts the first rollers 20 to rotate the retarder and also release the second ball gently into the storage rack. When a following ball is a largest ball, such as a ten pin ball, it will be intercepted by the second rollers 21 irrespective of whether the retarder is in its normal ball obstructing position or has been partially rotated by contact of a small ball with the rollers 20.

From the above description of the operation of the retarder, it is evident that the retarder can be used for retarding individual balls of different sizes or any combination of these balls rolling along the ball return track in proximity.

In Figs. 6, 7 and 8 there is illustrated a second embodiment of the invention. In Fig. 6 the cra-

dle 114 is shown in solid lines in full ball releasing position and in dotted lines in its normal ball obstructing position. The rollers 20, 21 and 22 are the same as the rollers shown in the first embodiment and occupy the same relative positions with respect to each other and to the ball return track portion 11c. However, in this embodiment, a relatively light weight cradle 114 is employed having side arms 116 instead of the plate-like side members 16 in the first embodiment. The first rollers 20 are mounted on relatively short upwardly extending arms 116a at the rearmost end of the cradle, while the second rollers 21 are mounted on longer upwardly extending arms 116b spaced upwardly of the arms 116a. The third rollers 22 are mounted on upwardly extending arms 116c located at the front of the cradle. The operation of this second embodiment of the invention in retarding balls of the same or different sizes or combinations of such balls is the same as that previously described for the first embodiment of the invention.

The embodiments of the invention in which an exclusive property or privilege is claimed are defined as follows.

I claim:

1. In a bowling alley structure including a ball return track, a bowling ball retarder for individual balls of different sizes and any combination of such balls rolling along the track in proximity, said retarder comprising a cradle mounted for rotation about an axis adjacent to said track and having a rear portion and a front portion on opposite sides of said axis, said rear portion extending above said track and said front portion extending substantially beneath said track when the cradle is in normal ball obstructing position, first means on said rear portion for intercepting a small ball rolling along said track, the momentum of said small ball causing said cradle to rotate to ball releasing position, second means on said rear portion normally out of position to intercept a small ball but movable into small ball intercepting position when a first small ball contacts said first means and causes said cradle to rotate to ball releasing position, said second means being normally in position to intercept a larger ball rolling along said track with the momentum of said larger ball causing said cradle to rotate to ball releasing position, third means on said front portion normally out of ball intercepting position but movable to intercept only a larger ball on rotation of said cradle by contact of a ball with one of said first and second means, and yieldable means urging said cradle to said normal position.

2. The ball retarder of claim 1 wherein each of said first, second and third means comprises a pair of rollers each located on opposite sides of said track.

3. The ball retarder of claim 1 wherein said first means is normally located a short distance above said track, said second means is located a greater distance above said track, and said third means is located at least partially beneath said track.

4. In a bowling alley structure including a ball return track, a bowling ball retarder for individual balls of different sizes and any combination of such balls rolling along the track in proximity, said retarder comprising a cradle mounted for rotation about an axis adjacent to said track and having a rear portion and a front portion on opposite sides of said axis, said rear portion extending above said track and

said front portion extending substantially beneath said track when the cradle is in normal ball obstructing position, a pair of first rollers on said rear portion normally located a short distance above said track and spaced on opposite sides thereof a distance such that they will be contacted by a small ball rolling along the track into said retarder, a pair of second rollers on said rear portion normally located a greater distance above said track and spaced on opposite sides thereof a distance such that all balls except the largest will pass thereunder, said second rollers being contacted by a small ball only when said first rollers are contacted by a first small ball to rotate said cradle and move the first rollers downwardly to ball releasing position, a pair of third rollers on said front portion normally located out of ball engaging position and spaced at opposite sides of said track a distance greater than the diameter of all but the largest balls, said third rollers being contacted only by a larger ball when said cradle is rotated to ball releasing position by contact of a ball with one of said first and second rollers, the contact of a small ball with said first rollers and a larger ball with said second rollers serving to rotate said cradle to ball releasing position, and yieldable means urging said cradle to said normal position.

5. The bowling ball retarder of claim 4 wherein said second rollers are located nearer said axis than said first rollers.

6. The bowling ball retarder of claim 4 wherein said cradle includes a pair of side members located on opposite sides of said track.

7. The bowling ball retarder of claim 4 wherein said cradle includes a pair of side members located on opposite sides of said track with one of each of said first, second and third rollers being mounted on a side member.

8. The bowling ball retarder of claim 4 wherein said track is provided with openings through which said first rollers pass when said cradle is rotated to ball releasing position by contact of a larger ball with said second rollers.

9. The bowling ball retarder of claim 4 wherein said front portion is provided with a bumper member normally located beneath said track, and said track is provided with a stop member against which said bumper member bears when said cradle has been rotated to ball releasing position by contact of a largest ball with said second rollers.

10. The bowling ball retarder of claim 4 wherein said cradle is provided with a positioning member normally bearing against a portion of the track when said cradle is in ball receiving position.

11. In a bowling alley structure including a ball return track, a bowling ball retarder for individual balls of different sizes and any combination of such balls rolling along the track in proximity, said retarder comprising a cradle mounted for rotation about an axis adjacent to said track and including a pair of side members on opposite sides of said track, said cradle having a rear portion and a front portion on opposite sides of said axis with the rear portion normally extending above said track and the front portion normally extending substantially beneath said track when the cradle is in normal ball obstructing position, a pair of first rollers on said rear portion normally located a short distance above said track and spaced on

opposite sides thereof a distance such that they will be contacted by a small ball rolling along the track into said retarder, a pair of second rollers on said rear portion normally located a greater distance above said track and closer to said axis than said first rollers and spaced on opposite sides of the track a distance such that all balls except the largest will pass thereunder, said second rollers being contacted by a small ball only when said first rollers are contacted by a first small ball to rotate said cradle and move the first rollers downwardly to ball releasing position, a pair of third rollers on said front portion normally located out of ball engaging position and spaced on opposite sides of said track a distance greater than the diameter of all but the largest balls, said third rollers being contacted only by a largest ball when said cradle is rotated to ball releasing position by contact of a ball with one of said first and second rollers, the contact of a small ball with said first rollers and a largest ball with said second rollers serving to rotate said cradle to ball releasing position, one of each of said first, second and third rollers being attached to a side member, and yieldable means urging said cradle to said normal position, said track being provided with openings through which said first rollers pass when said cradle is rotated to ball releasing position by contact of a largest ball with said second rollers.

12. The bowling ball retarder of claim 11 wherein said cradle is provided with a positioning member normally bearing against a portion of the track when said retarder is in ball receiving position, said front portion being provided with a bumper member normally located beneath the track and said track being provided with a stop member against which said bumper member bears when said cradle has been rotated to ball releasing position by contact of a largest ball with said second rollers.

13. In a bowling alley structure including a ball return track, a bowling ball retarder comprising a cradle mounted for rotation about an axis adjacent to the said track and having a portion to one side of said axis normally extending above said track, a first means on said portion for intercepting a ball rolling along said track, the momentum of said ball causing the cradle to rotate to ball releasing position, and a second means on said portion normally located a distance above said track sufficient to allow a relatively small ball to pass therebeneath but to block a relatively large ball and movable downwardly into small ball intercepting position when a first ball contacts said first means and causes said cradle to rotate to ball releasing position, and yieldable means urging said cradle to its normal position.

14. In a bowling alley structure including a ball return track, a bowling ball retarder for individual balls of different sizes and any combination of such balls rolling along the track in proximity, said retarder comprising a cradle mounted for rotation about an axis adjacent to said track and including a pair of side members on opposite sides of said track, said cradle having a rear portion normally extending above said track, a pair of first rollers on said rear portion normally located a short distance above said track and spaced on opposite sides thereof a distance such that they will be contacted by a small ball rolling along the track into said

retarder, a pair of second rollers on said rear portion normally located a greater distance above said track and spaced on opposite sides of the track a distance such that all balls except the largest will pass thereunder, said second rollers being contacted by a small ball only when said first rollers are contacted by a first small ball to rotate said cradle and move the first rollers downwardly to ball releasing position, the contact of a small ball with said first 10 rollers and a largest ball with said second rollers serving to rotate said cradle to ball releasing position, and yieldable means urging said cradle to said normal position.
